Attn:

UNITED STATES PATENT OFFICE.

SAMUEL BOTTOMLEY, OF PROVIDENCE, RHODE ISLAND.

DESIGN FOR WOVEN FABRIC.

SPECIFICATION forming part of Design No. 28,623, dated May 10, 1898.

Application filed March 31, 1898. Serial No. 675,992. Term of patent 14 years.

To all whom it may concern:

Be it known that I, SAMUEL BOTTOMLEY, of Providence, in the county of Providence and State of Rhode Island, have invented and produced a new and original Design for Woven Fabric, of which the following is a specification, reference being had to the accompanying drawings, forming part thereof.

Figure 1 is a view of the surface of the woven fabric. Fig. 2 is a sectional view of the same on the line A B.

The leading and material feature of my design consists in the closely-woven borders on each side of a central space, in which the warp and weft threads are placed a considerable distance apart.

In the drawings 3 3, indicate the borders; 4 4, the warp-threads of the borders, laid close together; 5 5, the warp-threads of the central part of the fabric, placed a considerable distance apart. The weft-threads 6 6 are

closely interwoven with all the warp-threads to form the closely-woven end 7 of the fabric. The weft-threads are then interwoven with the warp-threads 4 4 of the borders 3 3, and at intervals only are the weft-threads 8 8 extended across the fabric, thereby forming an open-woven central space with rectangular openings, presenting to the eye the appearance of an open grating inclosed with closely-woven borders.

Having thus described my invention, what I claim as new, and desire to secure by Letters Patent, is—

The design for woven fabric herein shown and described.

In witness whereof I have hereunto set my hand.

SAMUEL BOTTOMLEY.
